UNITED STATES PATENT OFFICE.

EDWARD H. GOHL, OF AUBURN, NEW YORK.

DECORATIVE LAMP-POST FOR STREET-LAMPS.

1,223,487.

Specification of Letters Patent.

Patented Apr. 24, 1917.

Application filed May 11, 1915. Serial No. 27,368.

To all whom it may concern:

Be it known that I, EDWARD H. GOHL, a citizen of the United States of America, and a resident of Auburn, in the county of Cayuga, in the State of New York, have invented new and useful Improvements in Decorative Lamp-Posts for Street-Lamps, of which the following, taken in connection with the accompanying drawings, is a full, clear, and exact description.

This invention relates to certain improvements in decorative lamp posts for street lamps, and refers more particularly to attachments for the heads of the posts for receiving and supporting relatively small flag staffs for decorative purposes.

In almost every municipality and village, it is customary during carnivals, fête days and other public celebrations to provide more or less elaborate decorations along the main thoroughfares or business streets usually by the extensive use of bunting, flags and strings of electric lights suspended across the streets and upon the fronts of buildings with little or no attempt at symmetry or harmony of colors or arrangement.

Furthermore, this work involves a considerable expense either to the merchants, property owners or municipalities, both for materials and for labor in installing and removing the decorations.

Many of the municipalities are now providing permanent decorative lamp posts bearing clusters of lights for evening and night decoration, and the main object of my present invention is to utilize these decorative lamp posts as a basis for more profuse and systematic street decoration which is effective both day and night, thereby producing a more harmonious effect, and at the same time relieving the merchants from an excessive burden of trouble and expense.

In other words, I have sought to provide simple and comparatively inexpensive devices capable of being easily and quickly installed upon and removed from the heads of the lamp posts for receiving and sustaining a plurality of flags which may be systematically arranged relatively to the cluster of lights without in any way interfering with the light radiation upon the walks or street.

Another object is to construct each flag support in such manner that the flag staffs

may be readily inserted therein or removed therefrom, while the supports are still in operative position upon the lamp posts.

Other objects and uses relating to specific parts of the device will be brought out in the following description.

In the drawings—

Figure 1 is a perspective view of a street decorative lamp post equipped with my improved decorative scheme.

Fig. 2 is an enlarged end view of one of the arms on the head of the post and one of my improved flag-supporting brackets thereon, portions of the flag staffs being shown in elevation and in section.

Fig. 3 is a side elevation of the parts shown in Fig. 2.

Fig. 4 is an enlarged vertical sectional view through one of the flag staff-supporting brackets, portions of the flag staffs being shown by dotted lines.

Figs. 5 and 6 are opposite end views of the same bracket.

Fig. 7 is an inverted plan of the bracket shown in Fig. 5.

In order that my invention may be clearly understood, I have shown the standard form of decorative street lamp posts —1—, as provided with a cluster of incandescent electric lamps —2— mounted upon the head of the post, said head being provided with a plurality of, in this instance four, radial arms —3—.

These arms are usually provided with opposite beveled sides —4— and a crowning upper face —5— to shed water therefrom, the sides —4— being disposed in downwardly converging planes, as shown more clearly in Fig. 2.

My invention consists in providing relatively small and comparatively inexpensive brackets —6— of cast iron or other suitable metal capable of receiving and supporting flag staffs —7— bearing any desired form of flag or streamers —8— selected for the occasion and symmetrically arranged to give the most pleasing and artistic effect.

Each bracket consists of a relatively broad base —9— and an upright standard —10— integral therewith, the base and standard being braced to each other by suitable reinforcing ribs —11—.

The base —9— is provided with a recess —12— in its lower side of substantially the

same as or slightly greater width than that of the upper face of the lamp post arms —3— to which it is adapted to be attached, thereby forming opposite longitudinally extending pendent flanges —13—.

5 The recess —12— is dove-tail in cross section to conform with the cross sectional contour of the upper portion of the arm —3— so that the flanges —13— are preferably disposed in downwardly converging planes to permit the flag-supporting brackets —6— to be easily slipped over the outer ends of and upon the arms —3— and adjusted to any desired position along said arms, each bracket 10 being held in its adjusted position by a clamping screw —14— engaged in a threaded aperture in one of the flanges —13— and against the adjacent side —4— of the arm —3—.

15 20 The lower face of the base —9— between the flanges —13— is slightly arched upwardly to conform to the crowning upper face of the arm —3— of the lamp post.

25 It is now clear that when the bracket is placed upon said arm in the manner just described, it is effectively locked against upward displacement by the inwardly converging flanges —13— engaging the downwardly converging sides —4—, while the clamping screw —14— serves to hold the bracket in its 30 adjusted position against endwise movement along said arm.

35 The lower side of the base —9— is also provided with a central lengthwise recess —15— for receiving and supporting one of the flag staffs —7— in a substantially horizontal position along the upper face of the post arm —3—, the portion of the base adjacent the recess —15— being provided with 40 one or more clamping screws —16— by which the corresponding flag staff may be firmly clamped between the base and upper face of said arm for holding the flag any desired distance beyond the outer end of the 45 arm and lamps mounted thereon.

50 The standard —10— of each bracket is preferably disposed at an angle other than a right angle to the base —6— and is provided with a lengthwise opening or passage —17— therethrough from the base to the top for receiving another one of the flat staffs —7—, said standard being preferably provided at its side adjacent the acute angle with lower and upper end bearings —18— and —19—, while the opposite side is provided with an intermediate bearing —20— substantially midway between the bearings —18— and —19—.

55 60 The inner faces of the bearings —18— and —19— are disposed in substantially the same straight line and terminate in beveled edges —21— to afford a firmer grip upon the adjacent side of the flag staff —7—.

65 In like manner the inner face of the bearing —20— is substantially straight and par-

allel with the inner faces of the bearings —18— and —19—, but is spaced apart from the straight line passing through the inner faces of said bearings —18— and —19— a distance slightly less than the diameter of the flag staff so that when the latter is inserted through the lengthwise opening —17— in engagement with the bearings —18—, —19— and —20— the portion thereof between the bearings —18— and —19— will be deflected slightly toward the acute angle between the standard and base of the bracket to produce an increased friction for more effectively retaining the flag staff in operative position, the ends of the bearing —20— being also beveled at —21— to additionally resist withdrawal of the staff.

70 75 These brackets are identical in construction and are, therefore, interchangeable and reversible upon the arms on the head of the post, but are usually placed in the manner shown in Figs. 1 and 3 so as to incline toward the outer ends of the arms from a vertical position.

80 85 It will be evident from the foregoing description that by using these brackets as a means of supporting the flags for street decorative purposes, they may be easily and quickly installed and as easily and quickly removed, or the brackets may be left permanently on the arms of the post and the flag staffs installed, removed or changed at will without material expense to the municipality or others who may have the street decorations in charge.

90 95 What I claim is:

100 105 1. A flag-supporting bracket for decorative street lamp posts comprising a base having its opposite longitudinal edges provided with pendent flanges to receive between them a portion of the head of the post and the under side of its intermediate portion provided with a recess adjacent said head portion for receiving a flag staff, and a standard rising from the center of the base 110 and inclining longitudinally thereof at an angle other than a right angle, said standard having a lengthwise opening for receiving a flag staff, and three bearings, two of which are located at one side of the passage 115 at opposite ends thereof and the other bearing at the opposite side of the passage between the end bearings, the transverse distance between the inner faces of the end bearings and inner faces of the intermediate 120 bearing being slightly less than the diameter of the flag staff which is to be inserted in said passage, whereby the portion of the flag staff adjacent the intermediate bearing will be deflected laterally between the end bearings.

125 130 2. In combination with the head of a street-lamp post, a flag-supporting bracket comprising a base secured to said head and a standard rising therefrom, the base having

a recess opening from its under side adjacent the head for receiving one flag staff, the standard having a lengthwise socket for receiving another flag staff, said socket having an elongated opening in one side and a bearing for the flag staff at the diametrically opposite side.

In witness whereof I have hereunto set my hand this 8th day of May, 1915.

EDWARD H. GOHL.
